US00D558597S

(12) **United States Design Patent** (10) **Patent No.:** **US D558,597 S**
(45) **Date of Patent:** ** *Jan. 1, 2008

(54) **EVACUABLE, RESEALABLE BAG**

(75) Inventors: **Michael E. Schreiter**, Appleton, WI (US); **Mladomir Tomic**, Appleton, WI (US); **Paul A. Tilmann**, Sherwood, WI (US); **Paul J. Tretina**, Glen Allen, VA (US)

(73) Assignee: **Alcoa Inc.**, Pittsburgh, PA (US)

(**) Term: **14 Years**

(21) Appl. No.: **29/250,551**

(22) Filed: **Nov. 20, 2006**

(51) **LOC (8) Cl.** **09-05**

(52) **U.S. Cl.** **D9/709**

(58) **Field of Classification Search** D9/704-710, D9/713-714, 720-722, 430-433, 414, 418, D9/424; 383/103, 107, 114, 200, 203, 205, 383/84, 113, 45, 47, 100, 108; 229/200, 229/87.06, 87.08; 426/106

See application file for complete search history.

(57) **CLAIM**

The ornamental design for an evacuable, resealable bag, as shown and described.

DESCRIPTION

FIG. 1 is a perspective view of the evacuable, resealable bag, showing an embodiment of the present design;

FIG. 2 is a front elevation view of the embodiment of the present design illustrated in FIG. 1;

FIG. 3 is a rear elevation view of the embodiment of the present design illustrated in FIG. 1;

FIG. 4 is a right elevation view of the embodiment of the present design illustrated in FIG. 1;

FIG. 5 is a left elevation view of the embodiment of the present design illustrated in FIG. 1;

FIG. 6 is a top plan view of the embodiment of the present design illustrated in FIG. 1;

FIG. 7 is a bottom plan view of the embodiment of the present design illustrated in FIG. 1.

FIG. 8 is an exploded perspective view of the present design illustrated in FIG. 1;

FIG. 9 is a front elevation view of a second embodiment of the present design without a writing surface;

FIG. 10 is a rear elevation view of a third embodiment of the present design wherein the writing surface is on the rear of the bag; and,

FIG. 11 is a front elevation view of a fourth embodiment of the present design illustrating an alternative valve location.
